UNITED STATES PATENT OFFICE.

JOHN B. KRAUSE, OF HILLSBORO, KANSAS.

STRAW-BINDING MACHINE.

Application filed December 21, 1923. Serial No. 682,042.

To all whom it may concern:

Be it known that I, JOHN B. KRAUSE, a citizen of the United States, residing at Hillsboro, in the county of Marion and 5 State of Kansas, have invented certain new and useful Improvements in Straw-Binding Machines, of which the following is a specification.

This invention relates to an improvement 10 in straw binders and has more particular reference to a machine for use in the binding of bundles of straw, the primary object of the invention residing in the provision of such a machine wherein the butt ends of the 15 outside strands of straw are employed for the binding agent.

An additional object of the present invention resides in the provision of means for picking out the outside strands of straw 20 and reversely bending the butt ends thereof whereby the same may be so acted upon by other parts of the machine for producing the binding agent.

Yet another object of the invention is to 25 provide a binding machine wherein the same may be operated by unskilled persons and wherein the same will operate effectively under all conditions, the machine being further characterized by the fact that a great 30 amount of bundles of straw may be bound in the minimum amount of time.

With the above and other objects in view as the nature of the invention will be better understood, the same comprises the novel 35 form, combination and arrangement of parts hereinafter more fully described, shown in the accompanying drawings and claimed.

In the drawings wherein like reference characters indicate corresponding parts 40 throughout the different views,

Figure 1 is a top plan view of a straw binding mechanism constructed in accordance with the present invention,

Figure 2 is a transverse cross sectional view upon a certain line thereof, taken on line 2—2 of Figure 1,

Figure 3 is a top plan view of the straw butt twisting mechanism of the present invention,

50 Figure 4 is a side elevational view thereof,

the carrying arm for said twisting member being shown in cross section,

Figure 5 is a detailed transverse cross sectional view of said straw twisting mechanism and taken substantially upon the line 55 5—5 of Figure 4,

Figure 6 is a detail vertical cross sectional view of the straw testing member, taken on the line 6—6 of Figure 7.

Figure 7 is a front elevational view of 60 the straw twisting member.

Figure 8 is a fragmentary side elevational view of the picking member of the present invention.

In carrying out this invention it is my 65 purpose to provide a binding mechanism to be employed in lieu of the usual costly and complicated binding mechanisms now employed in conjunction with harvesting machines, and in the present instance, 70 5 designates the floor or platform that is formed with a transverse elongated slot 6 through which extends the compressing mechanism including the usual clamping jaws 7—7 and that serve as a means for tightly compressing 75 the bundle of straw or wheat as the case may be, which bundle is designated by the reference character A. The usual straw or wheat bundle picking arm 7 upon one end of a shaft 8 is not of the essence of my invention and will not be claimed by me. 80

My invention per se embodies the provision of a stub shaft 9 journaled through an opening in the right angular portion 10 of the usual hollow horizontally disposed arm 11 85 through which is guided the before mentioned shaft 8 of the picking arm 7, this right angular portion 10 being formed upon or otherwise suitably secured to the platform 5. Upon the right hand end of this 90 stub shaft 9 there is keyed a sprocket gear 11' over which is trained a sprocket gear 12 that extends downwardly through the platform 5 due to the presence of an opening 13 therein and then trained over another 95 sprocket gear of the power mechanism, not shown.

Formed around the inner side of the opening in said right angular portion 10 of the hollow arm 11 is a boss 14, rigid with 100

which is a relatively large spur gear 15 and disposed for rotation around which is a suitably formed gear casing 16.

The inner end of said stub shaft 9 extends through the before mentioned boss 14 and is rigidly secured as at 17 to the hollow connecting rod 18 by a pair of laterally extending spaced parallel hollow arms 19 and 20, respectively.

10 Disposed for free rotation within the arms 19 and 20 are horizontal shafts 19' and 20' respectively, the inner ends of which extend within the gear casing 16 and are equipped with spur gears 19^a and 20^a, respectively, that are in mesh with the teeth of the before mentioned relatively large spur gear 15 rigidly secured to the boss 14 whereby when the arms 19 and 20 carrying said shafts are moved around the bundle of straw or grain A, said shafts 19' and 20' will be rotated.

15 The opposite ends of these horizontal shafts extend beyond the adjacent ends of the arms 19 and 20 and detachably secured to the projecting end of the shaft 20' is a finger 21 which seizes and turns outwardly the butt ends of the outer layers of straws of the bundle A as said shaft 20' is being rotated so that said out-turned ends of the straws will be subsequently received by a twisting device carried by the projecting end of the other shaft 19'.

20 The twisting device constitutes the provision of a sleeve 22 that is formed upon the free end of the shaft carrying arm 19, said sleeve being formed upon the inner side of the arm and pendant therefrom so as to be in a plane substantially vertical with respect to the longitudinal axis of the arm 19.

25 The front side of this sleeve 22 is open and formed upon the opposite edges of said opening are forwardly extending outwardly converging lips 23 for forming a mouth within which enter the reversely bent stub ends of the strands of the bundle A that have been acted upon by the finger 21, this action being clearly shown in Figures 1 and 2.

30 Journaled through an opening in the upper closed end of said sleeve 22 as more clearly shown in Figure 6, is a vertically disposed stub shaft 24 that is provided at its upper end with a gear 25 that is in mesh with a gear 26 upon the end of the shaft 19' it being noted that the upper end of said sleeve 22 is so formed as to provide a section of a gear casing for said gears for co-operation with a similar formed removable section 27.

35 The lower end of this stub shaft 24 is equipped with a relatively Z-shaped cross finger 28 the ends of which lie adjacent the internal wall of the sleeve 24 and which

serve as a means for effectively twisting the reversely bent butt ends of the straw strands after the same have passed into the sleeve through the mouth formed by said converging lips 23—23.

40 The lower end of the sleeve 22 is formed with a rearwardly extending discharge nozzle 28 and it will thus be seen that in operation the butt ends of the outside strands of straw or wheat in the bundle A, will be acted on by the finger 21 for reversely bending these butt ends into the position shown in Figures 1 and 2, after which the same will pass into the sleeve 23 at the point adjacent the bend, after which they will be engaged by the V-shaped member 28 upon the end of the shaft 24 which will thereby effectively twist these reversely bent ends of the strands of straw. A continued movement of the arm 19 around the bundle of straw will manifestly discharge the twisted strands for thereby forming an effective binding for the bundle of straw or wheat.

45 The specific operation together with numerous advantages of a straw binding machine of the present character will be at once appreciated by those skilled in the art, and even though I have herein set forth the most practical embodiment of the invention with which I am at this time familiar, it is nevertheless to be understood that minor changes may be made in the invention without departing from the spirit and scope of the appended claims.

50 Having thus described my invention, what I claim as new and desire to secure by Letters Patent is:—

55 1. In a bundle binding mechanism of the class described, a bundle compressor, a pair of inter-joined members movable around said bundle, means carried by one of said members for reversely bending the stub ends of the outside strands of the bundle, and means carried by the other of said members for inter-twisting said reversely bent strands and wrapping the same around the bundle. 105

60 2. In a bundle binding mechanism of the class described, a pair of spaced horizontal arms movable around said bundle, means carried by one of said arms for seizing and reversely bending the stub ends of the outside strands of the bundle, and means carried by the other of said arms for inter-twisting said reversely bent strands and wrapping the same around the bundle. 110

65 3. In a bundle binding mechanism of the class described, a bundle compressor, a support at one side of said compressor, a pair of interconnected spaced arms mounted upon said support for movement around the bundle held by the compressor, means carried by the foremost arm for seizing and reversely bending the stub ends of the outside strands of the bundle, and means car-

ried by the rearmost arm for inter-twisting said reversely bent strands and wrapping the same around the bundle.

4. In a bundle binding mechanism of the 5 class described, a bundle compressor, a support at one side of said compressor, a pair of inter-connected spaced arms mounted upon said support for moving around the bundle held by the compressor, a rotary

finger carried by one of the arms for seizing and reversely bending certain of the outside strands of the bundle, and means carried by the other arm for receiving, twisting, and discharging said reversely bent strands. 10 15

In testimony whereof I affix my signature.

JOHN B. KRAUSE.
